3,011,720 GAS VALVES

Richard O. Ives, Flossmoor, Ill., assignor to Harper-Wyman Company, Chicago, Ill., a corporation of Illinois

Filed July 21, 1959, Ser. No. 828,600
13 Claims. (Cl. 236—99)

The present invention relates to gas valves and has for its primary object the provision of a new and improved locking type of gas valve.

A further object of the present invention is to provide a new and improved thermostatic gas valve in which a single handle and valve stem are used both to control the open position of the valve and the temperature setting to be maintained by the valve.

A further object of the present invention is to provide a new and improved valve of the character set forth in the preceding paragraph in which the gas flow controlling valve element is connected to the handle and stem by disengageable clutch means and including new and improved means for requiring the flow controlling element to be rotated a predetermined angular distance to insure at least a minimum flow of gas before declutching can be effected.

In brief, the valve of the present invention is of the locking type. It includes a rotatable gas flow controlling element, such as a disc, mounted in a housing. The element is adapted to be rotated by valve stem means extending outside of the housing and which is both rotatable and axially movable relative to the housing. The stem and element are connected by means enabling the element to be rotated by the stem means. The valve is locked against rotation until the stem means is axially moved a short distance by means including a flat of short axial length on the stem and a flat on the housing abutting against the flat on the stem means. The flats are movable out of abutting engagement upon axial movement of the stem means, after which the latter and the gas flow controlling element can be turned. The rotatable gas flow controlling element and stem means are connected by disengageable clutch means so that a thermostatic control element can be adjusted independently of the gas flow controlling element upon rotation of the stem means subsequent to disengagement of the clutch means. The valve is so constructed and arranged that the disengagement cannot be effected until after the stem means and flow controlling element have been rotated a predetermined angular distance. This arrangement includes a flat on the valve stem means and a cooperating flat on the housing, one of the flat constituting structures being resilient in a radial direction to permit angular movement of the valve stem means. The flats constitute cooperating abutment means permitting axial movement sufficient only to disengage the locking means before the valve stem means is rotated and subsequently permitting further axial movement of the valve stem means to permit declutching of the latter from the flow controlling element. This feature may be used independently of the locking means.

Other objects and advantages of the present invention will become apparent from the ensuing description of an illustrative embodiment thereof, in the course of which reference is had to the accompanying drawings, in which:

FIG. 1 is a side elevational view of a valve constructed in accordance with the present invention with the valve and thermostatic actuating handle omitted and with the valve in an intermediate open position;

FIG. 2 is an end elevational view of the front end of the valve with the valve handle and associated bezel illustrated;

FIG. 3 is a front elevational view of the valve as illustrated in FIG. 1, but with the valve in its off position;

2

FIG. 4 is an enlarged axial cross-sectional view through the valve taken along the broken line 4—4 of FIG. 2 with the valve in an intermediate open position, but with the valve handle and stem means clutched to the gas 5 valve controlling element;

FIG. 5 is a further enlarged fragmentary axial cross-sectional view taken along the line 5—5 of FIG. 2 illustrating the operative positions of various operating parts when the valve is locked in its off position;

10 FIG. 6 is a fragmentary transverse cross-sectional view taken along line 6—6 of FIG. 5;

FIGS. 7 and 8 are views similar to FIGS. 5 and 6, but the valve unlocked in its off position ready to be turned; and

15 FIGS. 9 and 10 are views similar to FIGS. 5 and 6 but along line 4—4 of FIG. 2 with the valve unlocked, with the valve handle and stem means declutched from the gas flow controlling means and with the valve on, as in FIG. 4 and with the temperature control in a different 20 position of adjustment.

Referring now to the drawings and first primarily to FIGS. 1 to 4, the valve of the present invention is indicated as a whole by reference character 10. It is adapted to be mounted upon and supplied with gas from a gas

25 supply manifold 12, the mounting being effected by an externally threaded dependent nipple 14 within which is a gas inlet passageway 16. The valve includes, in the main, a valve body 20 within which is a chamber 22 (see FIG. 4) in which is mounted a thermostatically actuated

30 regulating valve indicated as a whole by reference character 24 controlling the flow of gas from a manually operable valve 26 including a rotary gas flow controlling valve element shown to be a rotor valve disc 28. The disc is adapted to be adjusted by a handle 30 which is 35 also utilized to select the temperature to be maintained. The valve and operating means may take various forms, that illustrated being of the type disclosed and claimed in the copending applications of Raymond F. Wiberg (case 2), Serial No. 817,519, filed June 2, 1959, and of

40 Norman M. Huff, Serial No. 817,518, filed June 2, 1959, and both assigned to the assignee of this application. Accordingly, the valve will not be described in detail, but only sufficiently to provide an understanding of the present invention which, as indicated heretofore, is directed to improved valve locking means and improved means 45 making it necessary to move the valve handle and gas flow controlling element a certain amount before the gas flow controlling element can be declutched.

The thermostatic valve 24 includes a relatively stationary valve seat 32 adapted to be moved axially for calibration purposes, as by a rotatable calibrating screw 34. The valve includes also a movable valve member 36 biased away from the valve seat by a spring 38 and the position of which is varied by thermostatic actuating

50 means. The position is varied as by a bimetallic lever 40 having one end 42 associated with the valve member 36 and its other end 44 operatively associated with the rotatable axially movable shaft 46 having an intermediate threaded portion 48 movable by the valve handle 30 to 55 vary the temperature to be maintained by the valve. The position of the lever 40 and, thus, of the valve member 36 is controlled by a thermostatically actuated power device 50 which may be of the diaphragm type and connected as by a capillary tube 52 to a suitable sensing unit (not shown) which may include a thermostatic capsule maintained in contact with the bottom of a cooking vessel placed on a burner to which the flow of gas is controlled by the valve 10. For convenience, the thermostatic power device 50 may be mounted upon an end

60 plate 54 closing the recess 22 and supporting also an outlet hood 56 communicating with a gas outlet passageway 65 70

58 and through which gas flows to the burner in conventional manner.

The flow of gas to the thermostatic valve is controlled by the manually operable rotatable rotor disc 28 which has a planar face 60 abutting against a planar face 62 formed on the valve body. The body and disc may be provided with suitable passageways interconnecting the passageway 16 and the recess 22 via the thermostatically operated regulating valve 24. The passageways may be such that they enable the valve disc 28 to be moved between off and full on positions to provide a manually regulatable flow of gas to the burner as between a low flame setting 64 and a high flame setting 66 indicated on the valve handle (see FIG. 2) in cooperation with an indicating dot 68 on a bezel 70 associated with the valve handle and supported upon a bezel mount 71 fixedly secured to the housing and having opposed slots 71A receiving tongues 70A of the bezel. The off position of the valve is indicated by a radial boss 72 on the handle when it is under the dot. In FIGS. 1, 2 and 4 the valve is shown at an intermediate position to provide an intermediate height flame. In this position, gas flows from the inlet passageway to rotor passage 74 and to a passageway 76 in the valve body leading to the thermostatic valve 24 and, hence, to the recess 22. For additional details of a construction which may be used, see the above referred to Wiberg application.

The rotor valve disc 28 is mounted in a housing or casing 78 having a larger diameter inner portion 80 and a smaller diameter axially extending outer portion 82, which are interconnected by a front wall 84 spaced some distance forwardly of the rotor 28. The casing is secured to the valve body by suitable means such as screw bolts 86.

The valve handle 30 is connected to the rotor valve disc 28 by valve stem means 90 and clutch means 92, whereby the rotor disc may be turned by or declutched from the valve stem means. The valve stem means 90 includes an outer stem portion 93 of generally D-shaped configuration provided by a flat 94 and upon which the handle 30 is secured. It includes also a hollow inner larger diameter portion 96 having axial slots 98 therein and connected to the valve regulating shaft 46 by a pin 100 at the end of the shaft, the pin and slot connection permitting relative axial movement between the shaft and stem means. The stem means is constructed as an assembly including also a drive washer 102 fixedly secured to the inner end of the stem portion 96 as by peening 104 and having radially inwardly extending keys 106 extending into opposed slots 98.

The clutch means 92 includes the diametrically opposed forwardly extending drive fingers or projections 108 on the drive washer and the central generally annular portion 110 of a drive yoke 112. The portion 110 has apertures 113 adapted to receive projections 108 in the clutch engaged condition. The drive yoke also has opposed rearwardly extending drive fingers 114 extending into oppositely disposed slots 116 in the rotor disc 28.

The drive yoke is rotatably mounted within the housing 78 as upon a tubular bearing element 120 fixedly secured within the smaller diameter forward extension 82 of the housing. The tube 120 has opposed outwardly extending front and rear flanges 122 and 124, the former of which abuts against the major portion of the front end of housing part 82 and the latter of which abuts against a shoulder 126 provided by counterboring at the region of the central opening in the yoke 112.

In order to prevent undesired rotation of the yoke and valve disc after disengagement of the clutch means, braking means in the form of a spring 130 is provided to frictionally restrain movement of the drive yoke, as described and claimed in the aforementioned Huff application, Serial No. 817,518. The spring 130 is disposed about the tubular bearing element 120 and between the annular part 110 of the drive disc and the vertical part 84 of the housing 78. The braking spring is constructed to have a concavo-convex shape before assembly, thereby to prevent an effec-

5 tive frictional force for restraint of movement of the yoke.

The valve disc 28 is held against the valve body and the stem assembly is held in its axially outermost position by a spring 132, one end of which is seated against the outer surface of the valve disc and the other of which bears against the inside of the drive washer 102, the contact between the spring and drive washer being through an annular spring guide 134. In the off position illustrated in FIG. 5, the stem assembly and valve handle are 10 drivingly connected to the valve disc 28 through the drive washer and drive yoke through the engaged clutch means, the engagement being effected by disposition of the drive washer fingers 108 in the apertures 113 of the yoke 112. To declutch or disengage the drive washer from the drive yoke, the valve handle and stem are moved inwardly 15 against the force of the spring 132 thereby to disengage the drive projections 108 on the drive washer from the yoke, as shown in FIG. 9. After such a disengagement, the valve and stem assembly can be turned independently 20 of the rotor disc valve 28 so that rotation of the handle turns only shaft 46 to adjust the temperature setting of the valve.

In accordance with the present invention, the valve is provided with improved locking means so that the valve handle cannot be turned until it has been pushed inwardly axially a predetermined angular distance. This locking means comprises a pair of flat abutting surfaces on the valve stem means and housing. In the illustrated embodiment of the invention, the two flats are the flat 140 on the housing and the flat 142 on the stem. As indicated, see FIGS. 5 and 6, the flat 140 on the housing is provided by a radially inwardly extending integral portion 144 of the housing and of which the flat 140 is a chordal surface of the opening therein through which the stem 90 extends. The flat 142 on the stem is simply a milled flat effectively on the larger diameter portion 96 of the stem. Viewing particularly FIGS. 5 and 6, it will be noted that the surfaces 140 and 142 are in abutting relation so that the handle, the stem assembly and the valve disc cannot be turned. To unlock the valve, the handle and stem assembly 30 are pushed inwardly to the position of FIG. 7. The axial length of the flat 140 on the stem is about the thickness, or slightly longer than the thickness of portion 144 of the housing, so that when the stem assembly is pushed inwardly to the position of FIG. 7 the stem assembly 40 can be turned.

In accordance with a further feature of the invention, the valve is so arranged that the handle stem assembly 50 cannot be declutched from the rotor valve disc 28 until after the former had been turned a predetermined angular extent, as of about 40 degrees. To accomplish this, co-operating abutment means are provided on the housing and stem assembly limiting axial movement of the stem assembly in the limited angular region so that declutching cannot be effected. Referring now particularly to FIGS. 5 and 8, the abutment means on the housing is constituted by a downwardly and forwardly extending tongue 150 on the bezel mount 71 and that on the stem by an abutment or shoulder 152 in the smaller diameter portion 93 of the stem which is formed as by slotting a portion 154 of the stem. The abutment 152, as shown in FIG. 7, is so located that the tongue engages it and prevents inward movement of the stem assembly sufficient to declutch the drive washer from the drive yoke. From FIG. 7 it will be noted that the tongue 150 is in engagement with abutment 152 and the drive fingers 108 remain in the apertures 113 in the drive yoke, thereby to drivingly couple the drive washer and the drive yoke.

In accordance with the present invention, the declutching is permitted after the stem assembly and valve disc having rotated a predetermined angular distance from the off position. This is accomplished by making the slot 154 a chordal slot as shown in FIG. 8 so that, upon rotation of the stem, the tongue is moved radially outwardly to lie on a circular part of the stem. Thus, referring now to FIGS. 9 and 10, after the valve handle

and stem assembly have been rotated so the tongue 150 is effectively moved from the slot 154, then the valve handle, stem assembly and drive washer 102 can be moved inwardly to declutch the drive washer from the drive yoke, as shown in FIG. 9. When decluched, the drive fingers 108 engage the rear surface of the drive washer and are no longer in effective driving engagement therewith.

It should be noted that the feature of preventing declutching of the handle and stem from the valve disc until the latter has been turned a predetermined extent can be utilized independently of the locking means. This can be accomplished by omitting the locking flats 140 and 142 or only the portion 144 of which the flat 140 is a part. When this change in construction is made, the valve handle and stem still have to be turned a predetermined extent before declutching can be effected.

Reviewing briefly the operation of the valve, it will be assumed first that the valve is in its off position as illustrated in FIGS. 5 and 6. At this time, the tongue 150 is in the slot 154, the locking flats 140 and 142 are in abutting relation to each other and drive washer 102 is fully coupled to the drive yoke 112, all as indicated in FIGS. 5 and 6.

In order to unlock the valve, the valve handle and stem assembly are pushed inwardly to the position illustrated in FIGS. 7 and 8. The inward movement is limited so that declutching cannot take place. However, the flats 140 and 142 are moved out of abutting relationship and flat 140 bears against the circular outer portion of the stem portion 93 so that the valve handle stem assembly and valve disc can be rotated. Movement of the drive assembly sufficient to permit declutching is prevented by engagement of tongue 150 against abutment 152, as shown in FIG. 7.

Once unlocked, the valve handle and parts connected thereto can be turned. During the turning operation, the tongue 150 is moved radially outwardly by the flat surface of slot 154 and once the tongue moves out of the slot, see FIG. 10, the valve handle can be pushed inwardly to effect declutching by movement of the drive fingers 108 out of the apertures 113 in the drive yoke, see FIG. 9. Once declutching is effected, the thermostat can be adjusted as desired with the valve disc disposed anywhere in the range between the declutching point and the high or full on position of the valve element. Thereafter, the temperature adjustment can be effected as desired.

To return the valve to off position, the valve handle is turned back toward off until the drive fingers 108 are moved into the apertures 113 by the action of the spring 132. Thereafter all the parts move in unison. It may be noted that fingers 108 are movable into the apertures 113 when the valve is being turned toward off even in the angular region in which declutching is prevented by engagement of tongue 150 against abutment 152. This results from the fact that upon return movement toward off position the tongue 150 can ride on the smaller diameter portion 93 of the stem with the aforesaid axial region, after which the stem can move axially outwardly to effect clutching.

While the present invention has been described in connection with the details of illustrative embodiments, it should be understood that these details are not intended to be limitative of the invention, except insofar as set forth in the accompanying claims.

What is claimed as new and desired to be secured by Letters Patent of the United States is:

1. A locking type thermostatic gas valve, including in combination, a rotatable control element, a housing for said element, axially extending valve stem means extending into said housing and being rotatable and axially movable relative to said housing, means including normally engaged clutch means disengageable upon a certain axial movement of the stem means and interconnecting

said stem means and element whereby said element can be rotated, means for locking said stem means against rotation including abutting flat surfaces generally facing the axis of the stem means on the stem means and housing, said flats being movable out of abutting relation upon axial movement of the stem means after which the latter can be rotated, and means requiring rotation of said stem means through a predetermined angle before said clutch means can be disengaged.

10 2. A locking type thermostatic gas valve, including in combination, a rotatable control element movable through a predetermined angular range between off and full on positions, a housing for said element, axially extending valve stem means extending into said housing and being 15 rotatable and axially movable relative to said housing, means including normally engaged clutch means disengageable upon a certain axial movement of the stem means and interconnecting said stem means and element whereby said element can be rotated, means for locking 20 said stem means against rotation including abutting flat surfaces generally facing the axis of the stem means on the stem means and housing, said flats being movable out of abutting relation upon axial movement of the stem means after which the latter can be rotated, and angularly 25 extending abutment means requiring rotation of said stem means through a predetermined angle substantially less than the angular extent of said range before said clutch means can be disengaged.

3. A locking type thermostatic gas valve, including in 30 combination, a rotatable control element, a housing for said element, valve stem means extending into said housing and being rotatable and axially movable relative to said housing, means including normally engaged clutch means disengageable upon a certain axial movement of the 35 stem means and interconnecting said stem means and element whereby said element can be rotated upon rotation of said stem means, means for locking said stem means against rotation including a flat of short axial length on said stem means and a flat on said housing 40 abutting against the flat on the stem means, said flats being movable out of abutting relation upon axial movement of the stem means after which the stem can be rotated, and means including opposed abutment structures on said stem and housing and one of which is radially 45 movable and requiring rotation of said stem means through a predetermined angle before said clutch means can be disengaged.

4. A locking type thermostatic gas valve, including in 50 combination, a rotatable control element, a housing for said element, valve stem means extending into said housing and being rotatable and axially movable relative to said housing, means including normally engaged clutch means disengageable upon predetermined axial movement of the stem means and interconnecting said stem means and element whereby said element can be rotated, means for locking said stem means against rotation including a flat of short axial length on said stem means and a flat on said housing abutting against the first flat, said flats being movable out of abutting relation upon axial movement of the stem means after which the latter can be 55 rotated, and means including an abutment on said stem means and a resilient abutment on said housing engaging said first mentioned abutment on said housing requiring rotation of said stem means through a predetermined angle before said clutch means can be disengaged by said predetermined axial movement of said stem means.

5. A locking type thermostatic gas valve, including in 60 combination, a rotatable control element, a housing for said element, valve stem means extending into said housing and being rotatable and axially movable relative to said housing, means including normally engaged clutch means disengageable upon predetermined axial movement of the stem means and interconnecting said stem means and element whereby said element can be rotated, means for locking said stem means against rotation including a 65

flat of short axial length on said stem means and a flat integral with said housing abutting against the first flat, said flats being movable out of abutting relation upon axial movement of the stem means after which the latter can be rotated, and means including an abutment on said stem means and a resilient abutment on said housing engaging said first mentioned abutment on said housing requiring rotation of said stem means through a predetermined angle before said clutch means can be disengaged by said predetermined axial movement of said stem means.

6. A locking type thermostatic gas valve, including in combination, a rotatable control element, a housing for said element, valve stem means extending into said housing and being rotatable and axially movable relative to said housing, means including normally engaged clutch means disengageable upon predetermined axial movement of the stem means and interconnecting said stem means and element whereby said element can be rotated, means for locking said stem means against rotation including a flat of short axial length on said stem means and a flat on said housing abutting against the first flat, said flats being movable out of abutting relation upon axial movement of the stem means after which the latter can be rotated, a bezel mount on said housing and means including an abutment of predetermined arcuate extent on said stem means and a resilient abutment integral with said bezel mount engaging said first mentioned abutment on said housing requiring rotation of said stem means through a predetermined angle before said clutch means can be disengaged by said predetermined axial movement of said stem means.

7. A gas valve, including in combination, a rotatable control element, a housing for said element, valve stem means extending into said housing and being rotatable and axially movable relative to said housing, means including normally engaged clutch means disengageable upon a certain axial movement of the stem means and interconnecting said stem means and element whereby said element can be rotated upon rotation of said stem means, and means including opposed abutment structures on said stem and housing and one of which is radially movable and requiring rotation of said stem means through a predetermined angle before said clutch means can be disengaged.

8. A gas valve, including in combination, a rotatable control element, a housing for said element, valve stem means extending into said housing and being rotatable and axially movable relative to said housing, means including normally engaged clutch means disengageable upon predetermined axial movement of the stem means and interconnecting said stem means and element whereby said element can be rotated, and means including an abutment on said stem means and a resilient abutment on said housing engaging said first mentioned abutment on said housing requiring rotation of said stem means through a predetermined angle before said clutch means can be disengaged by said predetermined axial movement of said stem means.

9. A gas valve, including in combination, a rotatable control element, a housing for said element, valve stem means extending into said housing and being rotatable and axially movable relative to said housing, means including normally engaged clutch means disengageable upon predetermined axial movement of the stem means and interconnecting said stem means and element whereby said element can be rotated, and means including an abutment on said stem means and a radially movable resilient abutment on said housing engaging said first mentioned abutment on said housing requiring rotation of said stem means through a predetermined angle before said clutch means can be disengaged by said predetermined axial movement of said stem means.

10. A gas valve, including in combination, a rotatable control element, a housing for said element, valve stem means extending into said housing and being rotatable

and axially movable relative to said housing, means including normally engaged clutch means disengageable upon predetermined axial movement of the stem means and interconnecting said stem means and element whereby said element can be rotated, a bezel mount on said housing, and means including an abutment of predetermined arcuate extent on said stem means and a resilient abutment integral with said bezel mount engaging said first mentioned abutment on said housing requiring rotation of said stem means through a predetermined angle before said clutch means can be disengaged by said predetermined axial movement of said stem means.

11. A gas valve, including in combination, a rotatable control element movable between off and on positions, a housing for said element, valve stem means extending into said housing and being rotatable and axially movable relative to said housing, means including normally engaged clutch means disengageable upon predetermined axial movement of said stem means and interconnecting the latter and the element whereby said element can be rotated, and means including cooperating abutments on said stem means and housing, of which one is effectively radially resilient, requiring rotation of said stem means through a predetermined angular distance away from off before said stem means can be moved axially to disengage said clutch means and permitting rotation of the stem means toward off position within said predetermined angular distance with the stem means in axial position to disengage the clutch means.

12. A gas valve, including in combination, a rotatable gas flow controlling element movable between off and on positions, an adjustable thermostatic valve, manually operable means for rotating said element and adjusting said thermostatic valve, disengageable clutch means operatively connecting said manually operable means to said element, said manually operable means being rotatable to move said element and adjust said thermostatic valve, and being axially movable to disengage said clutch means, and means including cooperating abutment structures on said valve and manually operable means, of which one is effectively radially resilient, requiring rotation of said means through a predetermined angular range when moving from off toward on position before said means can be moved axially to disengage said clutch means and permitting movement of said means toward off position in said range in axial position to disengage said clutch means.

13. A locking type thermostatic gas valve, including in combination, a rotatable control element movable between off and on positions, a housing for said element, valve stem means extending into said housing and being rotatable and axially movable relative to said housing, means including normally engaged clutch means disengageable upon predetermined axial movement of said stem means and interconnecting the latter and the element whereby said element can be rotated, means for locking said stem means against rotation including a flat of short axial length on said stem means and a flat on said housing abutting against the first mentioned flat, said flats being movable out of abutting relation upon axial movement of the stem means after which the latter can be rotated, and means including cooperating abutments on said stem means and housing, of which the one on the housing is effectively radially resilient, requiring rotation of said stem means through a predetermined angular distance away from off before said stem means can be moved axially to disengage said clutch means and permitting rotation of the stem means toward off position within said predetermined angular distance with the stem means in axial position to disengage the clutch means.
